UNITED STATES PATENT OFFICE

2,558,612

MACHINE WRENCH

Louis W. Falk, Milwaukee, Wis., assignor to The Falk Corporation, Milwaukee, Wis., a corporation of Wisconsin

Application January 5, 1945, Serial No. 517,517

10 Claims. (Cl. 74—1)

1

This invention relates to machine wrenches.

One object of the present invention is to provide a machine wrench particularly adapted for use with a torque loading device of the type disclosed in my copending application, Serial No. 517,516, filed January 5, 1945, now Patent No. 2,433,510.

Another object is to provide an improved power operated wrench capable of applying a heavy torque to a rotatable element without imposing a radial load of any substantial magnitude thereon.

Another object is to provide an improved power operated wrench for effecting relative rotation between two elements both of which are rotatable.

Another object is to provide a power operated wrench capable of applying a load with minimum friction loss so that the motivating force applied thereto may constitute a true measure of the load applied thereby.

Other more specific objects and advantages will appear, expressed or implied, from the following description of an illustrative embodiment of the present invention.

In the accompanying drawings:

Figure 1 is a view in elevation, partly in section, of a machine wrench constructed in accordance with the present invention and shown applied to an adjustable coupling of a torque loading device.

Fig. 2 is a transverse sectional view taken substantially along the line 2—2 of Fig. 1.

Fig. 3 is a transverse sectional view taken substantially along the line 3—3 of Fig. 1.

Fig. 4 is a fragmentary view in side elevation showing a part of the frame and cooperating shoe.

The machine wrench selected for illustration is shown applied to an adjustable coupling of the torque loading device disclosed in my above entitled copending application. The coupling shown comprises a ring 10 encircling and operatively connected to an end of a tubular shaft 11, and an abutting sleeve 12 encircling and operatively connected to an end of a shaft 13 that extends loosely through the shaft 11. In the torque loading device of said application the shafts 11 and 13 are operatively connected to opposite sides of a gear set so that by rotating the sleeve 12 relative to the ring 10 a torque load may be imposed upon the gear set. A series of clamp bolts 14 extending from a circular T-slot

15 in the ring 10 through an end flange 16 of the sleeve 12 serve to releasably fix the ring 10 to the sleeve 12, so as to maintain the torque

2

load thus imposed, both the ring 10 and sleeve 12 being rotatable with the shafts 11 and 12 to permit operation of the gear set for test purposes while subjected to said torque load.

5 The machine wrench shown comprises a pair of side arms 17 bolted or otherwise rigidly but detachably anchored to an intermediate connector member 18 to form a rigid frame adapted to partially embrace the coupling member above described. The member 18 may be replaced by others of different sizes so as to accommodate the frame to coupling members of various sizes. A heavy eye-bolt 19 resiliently mounted in the intermediate member 18 provides a convenient means for supporting the frame in the vertical operative position shown. In this instance each side arm 17 includes an integral back plate 20 that extends laterally and also downwardly from a vertical web 21, and a similarly shaped front plate 22 that is bolted or otherwise fixed to the web 21 and to spacers 23 carried by the back plate 20. The plates 20 and 22 of each arm 17 are parallel to each other and together form a channel for housing the operating parts of the wrench 25 which will now be described.

In this instance two opposed racks 24 are provided each toothed, as at 25, for meshing engagement with the externally toothed periphery of the coupling flange 16 at diametrically opposite points thereon. Each rack 24 is fixed by pins 26 or the like within the longitudinally slotted portion 27 of a carrier shank 28 guided for lengthwise movement between the plates 20 and 22 of each side arm 17.

35 One of the carrier shanks 28 is supported by a fluid actuated ram 29 working in and depending from a cylinder 30. The cylinder 30 is mounted in a socketed block 31 rockably supported by integral trunnions 32 journalled in the back and front plates 20 and 22 respectively of one of the side arms 17.

The other of the carrier shanks 28 is supported by a tubular extension 33 of a cylinder 34 containing a fluid actuated ram 35 projecting downwardly therefrom. The ram 35 is seated upon and fixed to a block 36 rockably supported by integral trunnions 37 journalled in the back and front plates 20 and 22 of the other of the side arms 17. The tubular extension 33 is longitudinally slotted, as at 38, to snugly receive the block 36 with which it cooperates to position and guide the cylinder 34.

45 Mounted in the manner above described, both carrier shanks 28 and the racks 24 carried thereby 50 may be swung into and out of engagement with

the coupling flange 16, and, when engaged with the flange 16, both racks 24 may be simultaneously actuated in opposite directions to rotate the flange by subjecting the upper ends of the cylinders 30 and 34 to fluid pressure through the pipes 39 and 40, respectively. In this connection it will be noted that, when fluid pressure is supplied to the cylinder 30, the ram 29 is actuated to lower the connected rack 24 and that, when fluid pressure is supplied to the cylinder 34, the ram 35 reacts against the block 37 to elevate the cylinder 34 and extension 33 and thereby elevate the connected rack 34. The two racks 34 thus function to simultaneously apply two forces of equal magnitude but in opposite directions to the coupling flange 16 to rotate the same without imposing a radial load thereon.

It will also be noted that each shank 28 is also freely movable lengthwise so as to directly transmit without loss the full force of the motivating fluid to the connected rack 24, so that the pressure of that fluid is a true measure of the force transmitted from each rack to the coupling flange 16.

Provision is made for releasably maintaining both racks 24 in engagement with the flange 16. In the wrench shown this is accomplished by the use of back-up rollers 41, one disposed behind each rack at a point opposite the zone of engagement of each with the coupling flange 16. Each roller 41 is shown mounted on an eccentric portion of a shaft 42 journaled in the back and front plates 20 and 22 of each side arm 17. Any suitable means, such as a lever 43 keyed or otherwise detachably fixed to either end of the shaft 42, is provided to rotate the shaft and thereby advance or retract the associated roller 41, and a detent 44 carried by the lever 43 and engageable in sockets 45 and 46 in the plate 20 or 22 serves to releasably retain the associated roller 41 in advanced or retracted position.

Provision is made for interlocking the side arms 17 of the frame with the coupling ring 10 so as to hold the latter against rotation when the coupling flange 16 is rotated by the racks 24. For this purpose the ring 10 is provided with a series of recesses 47 in the periphery thereof adapted to receive suitable shoes 48 carried by the frame. In this instance two opposed shoes 48 are provided, each being closely fitted in a notch 49 formed in the inner edge of a back plate 20 and detachably secured to the latter by a screw 50. The shoes 48 are arranged to project into diametrically opposed recesses 47 in the ring 10.

It will be noted that with the wrench applied in the manner indicated in Fig. 1, fluid pressure applied to the cylinders 30 and 34 will effect simultaneous operation of the racks 24 in such directions as to rotate the coupling flange 16 clockwise relative to the coupling ring 10. To effect rotation of the flange 16 in a counter-clockwise direction the wrench is removed and reversed, and the shoes 48 are reversed and transferred to the notches 49 in the front plates 22 of the side arms 17 of the frame so that they may be in positions to engage the ring 10 in the reversed position of the wrench. In this reversed position of the wrench the levers 43 are also preferably transferred to the other ends of the eccentric shafts 42 so as to provide for convenient manipulation of the rollers 41 in the new position.

Various changes may be made in the embodiment of the invention hereinabove specifically described without departing from or sacrificing

the advantages of the invention as defined in the appended claims.

I claim:

1. In a wrench for effecting relative rotation between two associated members, said wrench comprising a frame movable into and out of coacting relation with said members and having means releasably engageable with one of said members to hold the same against rotation relative to said frame, means movably mounted on said frame for releasably engaging the other of said members, and means for actuating said last named means to effect rotation of said last mentioned member relative to said frame.

2. In a wrench for effecting relative rotation between two associated members, said wrench comprising a supporting frame movable into and out of coacting relation with said members, a set of coacting elements carried by said frame for releasably engaging one of said members, a second set of elements carried by said frame for releasably engaging the other of said members, and means carried by said frame for actuating one of said sets of elements to thereby effect rotation of one of said members relative to the other.

3. In a wrench for effecting relative rotation between two associated members, said wrench comprising a supporting frame movable into and out of coacting relation with said members and having means for interlocking engagement with one of said members, a set of coacting elements movably mounted on said frame and engageable with the other of said members, and means carried by said frame for actuating said last named elements to effect rotation of said last named member relative to said frame.

4. In a device for effecting relative rotation between two associated members, said device comprising a supporting frame having means for releasably securing the same to one of said members, a pair of substantially parallel racks carried by said frame and engageable with the other of said members at diametrically opposite points thereon, and means carried by said frame for simultaneously actuating said racks in opposite directions to thereby rotate said last named member relative to said frame.

5. In a wrench the combination of a carrier frame movable into and out of coacting relation with the member to be rotated, a pair of substantially parallel opposed racks carried thereby for releasable engagement with said member, and means carried by said frame for simultaneously actuating said racks in opposite directions to thereby rotate said member.

6. In a device of the character described the combination of a portable frame, a pair of substantially parallel racks carried by said frame and relatively movable into and out of driving engagement with a member to be rotated at diametrically opposite points thereon, means for releasably retaining said racks in engagement with said member, and means carried by said frame for simultaneously operating said racks in opposite directions to thereby rotate said member.

7. In a device of the character described the combination of a portable frame, a pair of substantially parallel racks carried thereby for releasable engagement with an independently supported rotary member at diametrically opposite points thereon, and fluid actuated means carried by said frame for simultaneously actuating

said racks in opposite directions to thereby rotate said member.

8. In a device of the character described the combination with a substantially U-shaped portable frame comprising a connector member and a pair of spaced side arms detachably anchored thereto, of a pair of opposed racks each carried by one of said side arms for engagement with an element to be rotated, and means carried by each of said side arms for actuating the rack carried thereby.

9. In a wrench, the combination of a frame movable into and out of coacting relation with a member to be rotated and having side portions spaced apart to admit said member therebetween, means movably mounted on said frame for driving engagement with said member, and means on said frame for actuating said last-named means to thereby rotate said member relative to said frame.

10. In a device for effecting relative rotation between two relatively rotatable members, the combination of a frame having side portions spaced apart to admit said relatively rotatable members therebetween, means carried by said

5 side portions for interlocking engagement with one of said members to prevent relative rotation between the latter and said frame, and fluid actuated means carried by said frame for rotating the other of said members relative to said frame.
